UNITED STATES PATENT OFFICE.

S. HENRY HOLLAND, OF BROOKLYN, NEW YORK.

DESIGN FOR AN ALPHABET.

SPECIFICATION forming part of Design No. 14,143, dated July 31, 1883.

Application filed May 29, 1883. Term of patent 7 years.

To all whom it may concern:

Be it known that I, SAMUEL HENRY HOLLAND, of Brooklyn, in the county of Kings and State of New York, have invented an Improved Design for the Alphabet, of which the following is a specification.

In alphabet-letters and monograms for seals and stones, rustic designs have been employed, and in some instances leaflets have formed part of the design. In seal and stone engraving, curved lines are regarded as the most artistic in appearance. My alphabet design is especially adapted to seal-engraving, but not limited in that particular.

15 The design for the letters of the alphabet consists in the combination of curved stems and elongated tapering leaves with a stem and flower, as represented in the drawing.

The design of the stems, leaves, and flowers forming each letter is represented in the drawing, from which the beauty of the artistic effect will be apparent.

20 I claim as my invention—

The design of the alphabet, as described and represented, the same consisting in the combination of stems, leaves, and flowers, substantially as shown.

25 Signed by me this 25th day of May, A. D. 1883.

S. HENRY HOLLAND.
